[57] ABSTRACT

Methylnaphthalenes are obtained from a hydrocarbon mixture boiling within the range of 375° to 600°F containing alkyl naphthalenes and non-naphthalenes by distilling the hydrocarbon mixture to a boiling range of 460°-530°F and then treating this narrow boiling range fraction with a furfural extraction.

FIG. 1.

FIG. 2.

PURIFICATION OF ALKYL NAPHTHALENES BY DISTILLATION AND FURFURAL EXTRACTION

This is a continuation of application Ser. No. 214,317, filed Dec. 30, 1971 and now abandoned.

BACKGROUND OF THE INVENTION

1. Field of the Invention

This invention relates to a method of separating alkylnaphthalenes from a hydrocarbon feed comprising alkylnaphthalenes and non-naphthalenes.

2. Description of the Prior Art

It is known that naphthalenic compounds, for example, polycyclic aromatic compounds such as the alkyl-naphthalenes, are present in certain fractions derived from petroleum. Specifically, petroleum fractions which boil within the range of 375° to 600°F. generally contain substantial amounts of alkylnaphthalenes, such as mono-, di-, and tri-methylnaphthalenes and in smaller quantity, the ethylnaphthalenes. Recycle fractions, which are formed in the cracking of petroleum stocks and which include this boiling range, often contain major proportions of aromatic hydrocarbons that are mainly alkylnaphthalenes. Also present in significant quantities are the non-naphthalenes like the mono-cyclic aromatic hydrocarbons i.e. having one aromatic ring such as the alkyl benzenes, tetralin, indan, indene and their alkyl derivatives; certain tricyclic aromatic hydrocarbons, i.e. having three aromatic rings and non-aromatic hydrocarbons. Isolating these aromatic hydrocarbons from each other and from the aliphatic hydrocarbons is a difficult and complicated process. The separation is usually performed through selective solvent extraction.

Solvent extraction is a well known process for the separation of aromatic hydrocarbons from mixtures with nonaromatic hydrocarbons of similar boiling range. Furfural has been found to be an excellent selective solvent in the separation of hydrocarbons of relatively high boiling point, for example, hydrocarbons useful in the manufacture of lubricating oils and catalytic cracking feed stocks. Furfural extraction has also been found useful in the preparation of alkylnaphthalene concentrates as disclosed in commonly assigned U.S. Pat. No. 3,172,919 issued to Peter Frank Hagerty, Harold Foo-Heng Tse and Harland Jay Surrena issued Mar. 9, 1965. According to this process a fraction derived from cracked gas oil and boiling mainly in the range 440°-515°F. is extracted with furfural and followed by re-extraction of the furfural layer with a saturated hydrocarbon. In general, however, such alkyl-naphthalene concentrates contain compounds whose boiling points are so close to those of the methylnaphthalene isomers that methylnaphthalenes having purities higher than 95 percent, cannot be attained using this method even when the extract is redistilled. These methylnaphthalenes particularly the dimethylnaphthalenes are highly desirable articles of commerce in that they are intermediates for polyester resins which have outstandingly good properties for fiber applications.

SUMMARY OF THE INVENTION

We have now discovered an economical process whereby methylnaphthalenes are obtained from a hydrocarbon mixture boiling within the range of 375° to 600°F comprising alkylnaphthalenes including methylnaphthalene and dimethylnaphthalene, and non-

naphthalenes including monocyclic aromatics, tricyclic aromatics and non-aromatics which comprises:

- a. distilling said hydrocarbon feed in a distillation zone and withdrawing from said distillation zone a hydrocarbon fraction boiling mainly in the range of 460°-530°F;
- b. countercurrently extracting said hydrocarbon boiling mainly in the range of 460°-530°F. and comprising alkylnaphthalenes including methylnaphthalene and dimethylnaphthalene, monocyclic aromatics and nonaromatics with furfural solvent at a temperature in the range of 10°-150°F., the ratio of solvent to the total aromatics in the charge fraction being in the range of 0.75:1 to 7:1 on a volume basis;
- c. separating an extract phase from a raffinate phase;
- d. countercurrently contacting the extract phase at a temperature in the range of 10°-150°F. with saturated hydrocarbon of the C₅-C₈ range in amount of 0.5 to 2.0 volumes of said saturated hydrocarbon per volume of extract in the extract phase, whereby said saturated hydrocarbon mainly dissolves in the diluted extract phase and displaces therefrom non-aromatic and a minor amount of the monocyclic aromatics to form a reject phase containing said displaced non-aromatics and monocyclic aromatics and only a minor proportion of said saturated hydrocarbon;
- e. removing the reject phase;
- f. removing a furfural phase containing most of the alkylnaphthalenes and most of the C₅-C₈ saturated hydrocarbon; and
- g. separating mono and dimethylnaphthalene concentrate from said furfural phase.

BRIEF DESCRIPTION OF THE DRAWINGS

FIG. 1 is a schematic flowsheet of one embodiment of the invention.

FIG. 2 is a schematic flowsheet of a modification of the extraction step in the process.

A more detailed description will be found hereinbelow.

DESCRIPTION OF THE PREFERRED EMBODIMENTS

The charge stock used in the present invention can be any petroleum fraction containing naphthalene compounds. Typically the charge stock is a petroleum hydrocarbon fraction boiling within the range of 375° to 600°F. and containing at least a minor amount, e.g. 1-2% by weight, of naphthalenic compounds. Such fractions may have aromatic contents varying within the range of 25% to 97% usually contain between 50% and 95% aromatics depending upon the particular operation in which the petroleum fractions are produced. In general, the substituted condensed ring dicyclic aromatic hydrocarbons constitute about 20% to 80% of the total aromatic hydrocarbons present in the charge stock. The preferred hydrocarbon charge stocks are obtained in both catalytic and thermal cracking processes and in operations in which combinations of catalytic and thermal cracking steps are utilized. Thus, typically the charge stocks preferred for use in the present invention are petroleum hydrocarbons, such as cracked gas-oils, boiling between 375° and 600°F., having a gravity between 5° and 45° API, a sulfur content from negligible to 3% by weight or more, and containing at

least economically advantageous amounts of alkyl-naphthalenic compounds. However, hydrocarbons feeds having alkyl-naphthalene contents over 25 percent are preferred.

According to the invention the above described hydrocarbon feed is placed in a distillation zone and a hydrocarbon fraction boiling mainly in the range of 460°-530°F but preferably boiling mainly in the range of 480°-520°F is withdrawn. If mono- and dimethyl-naphthalenes are desired the 460°-530°F fraction is used. If dimethyl-naphthalene is desired then the narrower fraction should be used. The desired hydrocarbon fraction is first countercurrently extracted with a furfural solvent in limited amount but sufficient to extract essentially all of the dicyclic aromatics. Most of the non-aromatics and a portion of the monocyclic aromatics remain in the raffinate phase and are removed. The extract phase contains essentially all of the dicyclic aromatics, a major part of the monocyclic aromatics and also a substantial but minor amount of the non-aromatics. The extract phase is then treated with a C₅-C₈ saturated hydrocarbon, such as hexane or iso-octane, in a manner whereby essentially all of the non-aromatics and a portion of the monocyclic aromatics are displaced therefrom, being replaced by the C₅-C₈ saturated hydrocarbon. In some cases, prior to such treatment it may be necessary that the extract phase be diluted with more furfural solvent within a limited proportion range as hereinafter specified. Omission of this dilution step can vitiate the treatment with the C₅-C₈ saturated hydrocarbon and result in failure in achieve the desired displacement of the non-aromatics. Then treating with hexane or iso-octane in the proper amount, product can be obtained which contains nearly all of the methyl-naphthalenes and essentially none of the non-aromatics that were present in the feed.

Referring first to FIG. 1, a hydrocarbon fraction boiling in the range 375°-600°F derived from catalytic gas oil having an alkyl-naphthalene content of 48.5 percent by weight and a non-naphthalene content including alkylbenzenes, monocyclic aromatics and non-aromatics of 51.5 percent by weight is introduced through line 1 into distillation column 2 wherein a conventional distillation operation is performed. An overhead fraction boiling 460°F and lighter is withdrawn through line 3 to storage or further processing. A bottom fraction boiling 530°F and heavier is withdrawn through line 4 to storage or further processing. A side stream fraction being in the range of 460°-520°F is withdrawn through line 5 and introduced into cooler 6. The cooled fraction is withdrawn through line 7 and is introduced into the bottom of a countercurrent extractor 8. Furfural solvent, herein referred to as primary furfural is introduced to the top of the column through line 9 and flows downwardly therein countercurrent to the feed. The term "furfural solvent" as used herein refers to furfural itself of furfural containing dissolved water in any amount up to saturation at the temperature of the extraction operation. Column 8 should be operated at a temperature in the range of 10°-150°F., and more preferably 70°-110°F. In this operation it is important that the amount of primary furfural feed to the column be such that, on a volume basis, its ratio to the total aromatics in the feed lies in the range of 0.75:1 to 7:1 and more preferably 1:1 to 2:1. Under these conditions the extract phase, which is withdrawn from the column

through line 10 and is herein referred to as the "1st extract phase," will contain essentially all of the dicyclic aromatics, while the raffinate phase, which is removed via line 11, will contain a major proportion of the non-aromatics and some of the monocyclic aromatics.

The 1st extract phase in line 10 when necessary is admixed with an appropriate amount of additional furfural solvent, herein referred to as "secondary furfural," fed through line 12, and the mixture is sent to the top 10 of a second column 13. It is important that the amount of secondary furfural used be in the range of 0.15 to 2.5 volumes per volume of extract (i.e., gas oil hydrocarbons) in the extract phase and more preferably in the range of 0.25 to 1.25 vols./vol.

A C₅-C₈ saturated hydrocarbon or narrow-boiling range mixture of such hydrocarbons is feed to the bottom of column 13 through line 14 and therein passes upwardly in contact with the downflowing extract phase. Any paraffinic or naphthenic C₅-C₈ hydrocarbon or narrow-boiling range mixture thereof can be used for this purpose. The C₅-C₈ hydrocarbon material can contain a minor amount, for example, up to 10% by volume of aromatic components such as benzene and toluene. In the present description iso-octane will 20 be considered as the saturated hydrocarbon employed. Again, it is important that the amount of iso-octane be regulated within a specific range, namely, from 0.5 to 2.0 vol. per vol. of extract in the 1st extract phase fed to the top of column 13. More preferably, this ratio is in the range of 0.75-1.1 vols./vol. The temperature of this operation can be in the range of 10°-150°F., more preferably 70°-110°F., and it most preferably is about the same as the temperature used for the extraction in column 8. Contact of the iso-octane in the amount specified with the 1st extract phase causes most of the iso-octane to dissolve in the furfural and displace the non-aromatics. There is withdrawn from the top of the column through line 15 a reject phase which contains essentially all of the non-aromatics that were present in the 1st extract phase and only a small amount of the iso-octane used. From the base of the column a 2nd extract phase is removed through line 16. This material contains nearly all of the methyl-naphthalenes.

FIG. 2 illustrates a modification of the process in which the first column (not shown) is operated in the same manner as described above but the second column 20 is operated with a stripping section at the top. The secondary furfural from line 21 is split into two streams with part flowing to the top of the column and the remainder being introduced through line 22 into the 1st extract phase which passes through line 23 to an intermediate level in column 20. Iso-octane is fed to the bottom through line 25. The amount of furfural introduced through line 22 should be at least 15% by volume based on the extract in the 1st extract phase. The portion of the column above line 23 constitutes a stripping section in which the reject phase is countercurrently contacted with the remainder of the secondary furfural. This type of operation tends to give a still higher recovery of methyl-naphthalenes aromatic in the 2nd extract phase removed from the base of the column through line 24. The reject phase is removed through line 26.

In practicing either of the above-described embodiments, it is preferred to use furfural solvent which contains water and more preferably which is substantially

saturated with water at the temperature of operation. It has been found that the presence of water in the solvent lowers its capacity for monocyclic aromatics while leaving the capacity for dicyclic aromatics substantially unaffected. Hence the use of water in the primary and secondary furfural results in obtaining a dicyclic aromatic concentrate of higher purity without reducing the recovery of dicyclic aromatics.

By way of comparison from the data above it can be seen that the full boiling range material was not improved even with repeated furfural extractions. Note that beyond the fourth extraction the full boiling range material still contained 8-12% of the non-naphthalenic impurities while the narrower range was improved to 98% dimethylnaphthalenes in four extractions.

We claim:

TABLE I

	COMPARISON EXTRACTION		% METHYLNAPHTHALENEs	
	% NON-NAPHTHALENEs		Full Boiling Range (423-600°F)	Close Fractionated (460-520°F)
Starting Material	51.5	53.4	48.5	46.6
Furfural Extract No. 1	26.0	20.0	74.0	80.0
Furfural Extract No. 4	4.7	1.9	95.3	98.1

Comparative batch extractions at about 75°F were carried out to simulate the continuous process. Full boiling range and close-fractionated starting materials with analyses as shown in line 1 of Table I, were separately mixed thoroughly with 1 volume of furfural and the mixtures were then allowed to separate into two layers. The hydrocarbons in the furfural layers were analyzed are found to be as shown in line 2 of Table I, labelled Furfural Extract No. 1. Each furfural extract was then mixed with 1 volume of iso-octane and allowed to separate into two layers, whereupon the iso-octane layer was removed. After a total of three such iso-octane extractions, the hydrocarbons in the furfural layer were found to have the analyses shown in line 3 of Table I, labelled Furfural Extract No. 4.

The surprising and beneficial results of close fractionation before extraction can be seen by comparing the analyses of the furfural extracts of the starting materials. In spite of the fact that the close-fractionated starting material actually had a slightly lower methylnaphthalene content than did the full-boiling range material, the furfural extracts of the close-fractionated material had a significantly higher methylnaphthalene content.

Another beneficial effect of the present process is that it enhances the efficiency of the extraction step. To show this effect the following data are presented in the following Table II.

TABLE II

	VAPOR PHASE CHROMATOGRAPHIC ANALYSIS OF THE EXTRACTIONS

1. Process for separating mono and dimethylnaphthalene from a hydrocarbon feed comprising alkylnaphthalenes including methylnaphthalenes and dimethylnaphthalenes and non-naphthalenes including monocyclic hydrocarbons and non-aromatic hydrocarbons, said feed boiling in the range from 375-600°F. and containing 25-97% aromatics and over 25% alkylnaphthalenes which comprises:
- distilling said hydrocarbon feed in a distillation zone;
  - withdrawing from said distillation zone a hydrocarbon fraction boiling mainly in the range of 460°-530°F;
  - countercurrently extracting said hydrocarbon fraction boiling mainly in the range of 460°-530°F. comprising alkylnaphthalenes, monocyclic aromatics, tricyclic aromatics and non-aromatic hydrocarbons with furfural solvent at a temperature in the range of 10° to 150°F., the ratio of furfural to the total aromatics in the charge fraction being in the range of 0.75:1 to 7:1 by volume;
  - separating an extract phase from a raffinate phase;
  - countercurrently contacting the extract phase at a temperature in the range of 10° to 150°F. with saturated hydrocarbon of the C₅-C₈ range in amount of 0.5 to 2.0 volumes of said saturated hydrocarbon per volume of extract in the extract phase, whereby said saturated hydrocarbon mainly dissolves in the diluted extract phase and displaces therefrom non-aromatic hydrocarbons and a minor amount of the monocyclic aromatics to form a reject phase containing displaced non-aromatics, monocyclic aromatics and only a minor proportion of said saturated hydrocarbon;
  - removing the reject phase;
  - removing the furfural phase containing most of the mono and dimethyl naphthalenes and most of the C₅-C₈ saturated hydrocarbon; and
  - separating the mono and dimethylnaphthalene concentrate of higher than 95% purity from said furfural phase.
2. Process according to claim 1 in which the extract phase in step (d) is diluted with furfural solvent in an amount of from 0.15 to 2.5 volumes of diluent solvent per volume of extract in the extract phase before step (e).

3. Process according to claim 1 wherein said furfural solvent is furfural substantially saturated with water.

4. Process according to claim 1 wherein said saturated hydrocarbon is isooctane.

5. Process for separating dimethylnaphthalene from a hydrocarbon feed comprising alkylnaphthalenes including methyl naphthalenes and dimethylnaphthalenes and non-naphthalenes including monocyclic aromatic hydrocarbons, and non-aromatic hydrocarbons, said feed boiling in the range from 375°-600°F. and containing 25-97% aromatics and over 25% alkylnaphthalenes which comprises;

a. distilling said hydrocarbon feed in a distillation zone;

b. withdrawing from said distillation zone a hydrocarbon fraction boiling mainly in the range of 480°-520°F.,

c. countercurrently extracting said hydrocarbon fraction boiling mainly in the range of 480°-520°F. comprising alkylnaphthalenes, monocyclic aromatics, tricyclic aromatics and non-aromatics hydrocarbons with furfural solvent at a temperature in the range of 10°-150°F., the ratio of furfural to the total aromatics in the charge fraction being in the range of 0.75:1 to 7:1 by volume,

d. separating an extract phase from a raffinate phase;

e. countercurrently contacting the extract phase at a temperature in the range of 10° to 150°F. with satu-

rated hydrocarbon of the C₅-C₈ range in amount of 0.5 to 2.0 volumes of said saturated hydrocarbon per volume of extract in the extract phase, whereby said saturated hydrocarbon mainly dissolves in the diluted extract phase and displaces therefrom aliphatic hydrocarbons and a minor amount of the monocyclic aromatics to form a reject phase containing displaced non-aromatics monocyclic aromatics, and only a minor proportion of said saturated hydrocarbon;

f. removing the reject phase;

g. removing the furfural phase containing most of the dimethylnaphthalenes and most of the C₅-C₈ saturated hydrocarbon; and

h. separating dimethylnaphthalene of higher than 95% purity from said furfural phase.

6. Process according to claim 5 in which the extract phase in step (d) is diluted with furfural solvent in an amount of from 0.15 to 2.5 volumes of diluent solvent per volume of extract in the extract phase before step (e).

7. Process according to claim 5 wherein said furfural solvent is furfural substantially saturated with water.

8. Process according to claim 5 wherein said saturated hydrocarbon is isooctane.
